UNITED STATES PATENT OFFICE

DONALD McG. NEWTON, OF MONTCLAIR, NEW JERSEY, ASSIGNOR TO MACARTHUR CONCRETE PILE CORPORATION, OF NEW YORK, N. Y., A CORPORATION OF NEW YORK

METHOD OF FORMING PILES

Application filed November 2, 1927. Serial No. 230,406.

This invention relates to an improved pile and method of forming the same.

It is an object to provide an article of this character by means of a method which may be readily practiced, the resultant article embodying a strong structure encased in the ground in such manner that a load placed upon the pile will be supported effectually.

A further object of the invention is that of furnishing a pile and an improved method of forming the same, which latter may be practiced economically and by relatively unskilled labor to provide an article which will render effective service for an indefinite period of time.

With these and further objects in mind, reference is had to the attached drawings wherein there is illustrated one practical embodiment of the invention, and in which:

Figs. 1, 2 and 3 are sectional side views of successive steps in the forming of a pile; and

Fig. 4 is a similar view showing the resultant article.

According to the present invention a driving casing is primarily sunk into the ground. This may be accomplished conveniently as in Fig. 1 by disposing within the casing 5 a core or ram 6, the lower end of which may be tapered as at 7 if desired. The sinking or driving of these elements into the ground is accomplished ordinarily by the use of a pile driving mechanism which acts upon the upper end of the casing. To this end the core may at its upper end support, or have as an integral part, a driving head 8 against which the impelling member of the pile driving mechanism strikes, it being obvious that by means of the core the entrance of earth or foreign matter into the casing is prevented as the latter is sunk. This is aside from the fact that by means of the core the casing is reenforced to prevent any likelihood of damage incident to the strains of driving or sinking the same.

The driving casing has an exterior diameter

approximately equal to the diameter which the finished pile is to have and after it has been sunk to the proper depth the core or ram is removed, as has been shown in Fig. 2. Thereupon there is introduced into the casing a permanent casing 9 which is filled, as has been indicated at 10 in Fig. 3, with a concrete mixture of suitable consistency. Obviously, a space will exist between the driving casing and the permanent casing so that the latter may be introduced freely into the former. This space has been somewhat exaggerated in Fig. 3 for the purpose of illustration. But in any event, this space, as well as the void created by the withdrawal of the driving casing (hereinafter described) is filled so that there is no possibility of play coming into existence between the finished core unit and the supporting medium therefor.

To this end preferably a grout mixture of a somewhat fluid nature may be introduced into this space. This is capable of accomplishment after the filling of the permanent casing, by either pouring the grout mixture into the space existing between the casings and permitting the same to flow downwardly by gravity, or as has been shown in Fig. 3, by withdrawing the driving casing from around the permanent casing to provide what might be termed a reservoir, filling the latter with a mass of grout 11 and thereupon withdrawing the first-named casing, resulting in the grout mixture flowing into the space extant between the casings and also filling the void left by the withdrawal of the casing 5.

It will be obvious in this connection that if, due to conditions of temperature, consistency of the mixture, smallness of the space existing between the casings, or for any other reasons, the grout mixture does not flow readily as desired, that a head or piston, indicated in dotted lines at 12 in Fig. 3, may bear, either by its own weight or under force, against the

upper surface of the body 11, resulting in the mixture being expressed into the space desired as the casing 5 is withdrawn.

Irrespective of the manner of accomplishment of the latter steps, a finished pile is presented which according to the present exemplification includes a core 10 of concrete, an outer layer of grout, and an interposed metallic sleeve provided by the permanent casing. As such, it will be understood that no spaces will exist between the outer face of the pile and the supporting medium and consequently no play can come into existence irrespective of the manner in which the load is disposed upon the pile.

It will also be apparent, in this connection, that the outer layer will key into all irregularities of the ground, thus serving, to a certain extent, to resist vertical strains imposed upon the pile body. This is aside from the fact that the outer layer will act to protect the permanent casing against corrosion incident to direct contact with the supporting medium.

At this time it will be appreciated that the configurations of the various elements employed, and the specific texture of the mixture utilized might be varied in numerous respects according to the finished pile which is to be produced. Also, the steps of the method may be modified in various aspects without departing from the spirit of the invention.

Thus, among others, the objects specifically aforementioned are accomplished, the specific teachings of the invention being as aforesaid susceptible to numerous changes, without departing from the spirit thereof as defined by the claims.

Having described my invention, what I claim as new and desire to secure by Letters Patent is:

1. A method of forming a pile in which a pair of telescoped casings are employed, which includes filling the interior and imperforate casing with a cement material and flowing material of a like character into the space occupied by the outer casing while withdrawing the latter from around the inner casing and such latter material being in direct contact with the ground within which said pile is disposed and supported.

2. The method of forming a pile by employing a pair of telescoped imperforate casings, which includes filling the inner casing with a cement mixture, withdrawing the outer casing while flowing a grout mixture into the voids left by such withdrawal, such mixture thus occupying a position encircling the first-named casing and forming a distinct layer separate from the cement mixture and in direct contact with the material within which pile is disposed and supported.

3. The method of forming a pile by employing a pair of telescoped imperforate casings, which includes filling the inner casing

with core material, partially withdrawing the outer casing to provide a reservoir above the first casing and the core within the same, filling such reservoir with a similar material and causing the latter to flow through the space existing between such casings and into the voids created by the withdrawal of the outer casing, such latter material providing a layer wholly segregated by the inner casing from the core material and in direct material contact with the ground within which said pile is disposed and supported.

In testimony whereof I affix my signature.

DONALD McG. NEWTON.
